(57) **CLAIM**

The ornamental design for a digital otoscope camera with USB cable, as shown and described.

DESCRIPTION

FIG. 1 is a front perspective view of a digital otoscope camera with USB cable, showing my new design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof; and,

FIG. 6 is a bottom plan view thereof.

The broken lines consisting of evenly spaced lines in the drawings depict parts of the digital otoscope camera with USB cable that form no part of the claimed design, while the broken lines consisting of dash-dot-dash lines in the drawings depict the boundary of the claimed invention and it is understood that the claim extends to the boundary that forms no part of the claimed design.

The USB cable is shown with symbolic breaks in its lengths. The appearance of any portion of the article between the break lines forms not part of the claimed design.
